RADIATOR

Leopold Lithman, New York, N. Y.

Application May 4, 1933. Serial No. 669,304

7 Claims. (Cl. 257—141)

This invention relates to radiator structures and has for its object to provide a radiator of very simple construction, composed of a number of similar easily assembled units permitting the 5 radiator to be built up to any suitable size to meet various heating requirements. The invention is particularly adapted to electrically heated radiators, although it may be used very successfully in connection with other kinds of heat. A further object of the invention is to provide a radiator having a very great degree of heating efficiency.

A still further object of the invention is to provide a radiator composed or built up of like parts 15 so that great ease in the manufacture and assembly of the device is possible.

More specifically, the invention contemplates a radiator composed of a plurality of separated yet closely spaced, flat, tubular sheet metal open- 20 ended cells or flues which are held in their spaced relationship by means of elongated, relatively thin cast metal spacers which are apertured and located in alignment to co-operate with apertures formed in the flue walls to form several water- 25 circulating passages through which a free circulation of the heated water may be had to heat air passing upward through the flues and around the spacers.

These and other objects are attained by the 30 structure of this invention, a more particular description of which appears hereinafter.

Referring to the accompanying drawing, in which the preferred embodiment of the invention is shown, Figure 1 is a vertical sectional view 35 through the improved radiator, taken on the line 1—1 of Figure 3, looking in the direction of the arrows;

Figure 2 is a sectional view on the line 2—2 of Figure 1, looking in the direction of the ar- 40 rows;

Figure 3 is a plan view of the improved radiator;

Figure 4 is a side elevation of a part of one of the flues or cells showing the openings formed 45 therein;

Figure 5 is a view of one face of one of the spacing elements or flue separators;

Figure 6 is a side elevation of the element dis- closed in Figure 5;

50 Figure 7 is a face view of a modified spacing element or separator; and

Figure 8 is a face view of one of the end mem- bers of the radiator assembly.

The improved radiator is provided with a num- 55 ber of spaced cells or flues 10, each of which is

formed of elongated sheet metal plates 10a as clearly shown in Figures 1 and 3, the longitudinal edges of one of the plates 10a being bent at 11 to embrace the longitudinal edges of the other section so that the two plates thus united co-operate 60 to form a relatively flat, tubular open-ended flue. These flues or cells 10 are held in spaced-apart relationship by cast metal spacers or separators 12, the construction of which is clearly shown in Figures 5, 6, and 7. Each of the separators con- 65 sists of a relatively flat section of metal provided with openings 13, 14 and 15 and edge recesses 40. One face of each of the separators is pro- 70 vided with a continuous projecting wall or rib 16, and the opposite face is provided with a cor- responding groove 17.

The radiator in its assembled condition is shown in Figures 1 and 2 wherein it will be seen that a number of the flues are placed together with the separators interposed between the two wall 75 plates 10a of each flue and also between the walls of the adjacent flues. The ribs 16 in each of the separators fit into complementary grooves pressed in the wall plates 10a of each of the flues. These pressed out grooves in the wall plates of the flues 80 have their convex side extending into the grooves 17 provided in one of the faces of the separators. This interlocking fit of the flue walls and sep- 85 arators forms an effective water-tight bond between the flues and separators.

The walls 10a of the flues are each provided with openings 18, 19 and 20 corresponding to and registering with the similar openings 13, 14 and 15 in the separators 12 when the radiator is assem- 90 bled. Consequently, when the flues and separa- 95 tors are placed together, a plurality of water-cir- culating passages are formed through the flues and separators as clearly shown in Figure 1.

At each end of the radiator assembly is pro- 95 vided an end element or closure member as shown at 21 and 22 in Figures 1 and 3. Each of said end elements is provided with passages 23, 24 and 25 registering with the similar openings 18, 19 and 20 in the flues and also with the openings 13, 14 and 15 provided in the separators 12. In the end 100 elements 21 and 22 the several passages 23, 24 and 25 do not pass completely through the mem- bers but are connected by a vertical passage 26 which leads to a nipple 27 to which a pipe 28 is connected. One of these pipes 28 constitutes an 105 inlet pipe and the other an outlet pipe for water in the separators, the openings 18, 19 and 20 in 110

the flues, and the passages 23, 24, 25 and 26 in the end elements 21 and 22.

In the operation of the radiator, the air passes upwardly through the flues and moves upwardly 5 around the spacers 12 which present their narrower ends at the tops and bottoms of the flues and thus offer little resistance to the passage of air through the flues, and passes upwardly and outwardly through the flues to heat the room.

10 The air passing around the heated members 12 and heated flue walls 10a becomes rapidly heated.

The radiator assembly is held together by the lengthy threaded rods or bolts 29 and 30 which extend through the end member 21, pass through 15 the recesses 40 in the separators 12, through the holes 41 in the flue walls 10a, and thread into the end member 22, thus acting to hold the flues 10, spacers 12 and end members 21 and 22 securely clamped together in operative assembly.

20 In the construction of the separators shown in Figure 5, each separator is provided with a relatively large central aperture 14 and smaller upper and lower apertures 13 and 15, the flue walls 10a being similarly apertured as clearly shown in Figure 4. In the modification shown in Figure 7, the separator is provided with four like apertures 42. When separators of this kind are used, flue walls and end members similarly apertured are also used in co-operation with such separators.

25 What I claim is:

30 1. A radiator structure having a body portion composed of a plurality of like apertured cast metal elements placed together to form a water circulating chamber, a plurality of flues comprising open-ended tubular elements having parts of their walls interposed between the apertured cast metal elements, the portions of the walls of said flues located between the cast metal elements being apertured similarly to the cast 40 metal elements, so that an uninterrupted water circulating chamber is formed by the cast metal elements and the flues.

45 2. A radiator structure consisting of a plurality of open-ended tubular flues, a plurality of spacing members located between the walls of the flues, each of said spacing members being provided with several openings extending through 50 it, the various spacing members being placed together with their openings in registration so that the various spacing members co-operate to form several separate water-circulating passages, the walls of the flues being provided with openings corresponding in shape and number to those in each of the spacing members so that an un- 55 impeded passage of water through the spacing members and flue-wall openings is provided.

3. A radiator structure having a body portion composed of a plurality of like, apertured, elements placed together to form a water-circulating chamber having several passages through it, flues positioned between the elements and projecting from the same, the faces of the elements being ribbed and recessed and the walls of the flues being complementarily ribbed and recessed to receive the faces of the elements and form a water-tight joint therewith.

4. In a radiator assembly, flues with spacing elements located between them, the spacing elements having several water passages through them, the spacing elements being located between the flue walls and co-operating with similar openings in said flue walls to form several spaced water-circulating passages.

5. In a radiator assembly, spaced tubular flues, tubular spacing members located between the walls of the flues, each of said spacing members having several passages extending through it, the walls of the flues being apertured to correspond in number and shape to the passages in the spacing members, the faces of the spacing members being ribbed and recessed and the faces of the 100 flue walls being similarly ribbed and recessed.

6. A radiator structure having a body portion composed of a plurality of like, apertured, cast metal elements placed together to form a water-circulating chamber provided with several separate passages extending through it, a plurality of flues comprising open-ended tubular elements having sheet metal walls, parts of said walls being interposed between the apertured cast metal elements, the parts of the walls of said flues located 110 between the cast metal elements having apertures conforming in number and shape to the apertures in the cast metal elements so that an uninterrupted water-circulating chamber having several passages extending through it is formed 115 by the cast metal elements and the flues.

7. In a radiator assembly, flues with spacing elements located between them, the spacing elements having several water passages extending through them and having recesses in their longitudinal edges, said spacing elements being located between the flue walls and co-operating with similar water passages formed in the walls to form several spaced water-circulating passages, closed 120 end members at the ends of said water-circulating 125 passages and bolts connecting said end members and clamping the flues and spacing elements between said end members, said bolts being located in the recesses in the spacing elements.
